UNITED STATES PATENT OFFICE

LEWIS J. BAZZONI, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY

MACHINE FOR GROOVING HEELS

Application filed February 7, 1929. Serial No. 338,285.

This invention relates to machines for and methods of operating on heels and is herein exemplified in its application to forming grooves or slots in the breasts of wood heels adjacent and parallel to the corners formed by the breasts and the sides of the heels to receive and retain the margins of coverings extending around the rear and sides of the heels.

10 In United States Letters Patent No. 1,704, 204, granted on March 5, 1929, on application of William H. Nutt, there is described a Cuban heel having two side cover retaining grooves or slots arranged adjacent to and 15 parallel with the corners or edges formed by the breast and the sides of the heel.

An object of the present invention is to provide a machine constructed and arranged for forming in the breasts of Cuban heels 20 cover retaining grooves such as those illustrated in Figs. 6 to 10, inclusive, of the above-mentioned patent.

With the above object in view, one feature of the present invention consists in the provision of means for supporting a heel placed thereon, grooving or slotting means extending beyond the supporting means, and a gage constructed and arranged to engage the side of the heel to facilitate the guiding of the 30 heel over the supporting means as the heel is moved past the grooving means to form a groove or slot in the breast of the heel.

Another feature of the invention consists in the provision of a machine for forming 35 grooves such as those above-mentioned, which machine is so organized as to insure against the splitting of the heel. To this end and in accordance with the illustrated embodiment of the invention, a table which 40 supports the heel for operation thereon by the grooving means and the gage which engages the side portion of the heel may be tilted relatively to the grooving means to provide for cutting grooves at varying angles 45 in the heel breast.

A still further feature of the invention consists in the provision of a machine for forming grooves such as above described at various distances from the breast corners of 50 the heels. The illustrated machine is pro-

vided with means for varying the distance between the gage and the grooving means in order to change the position of the grooves to be cut in the breasts of the heels relatively to the breast corners of the heels.

In accordance with a further feature of the invention, the machine is provided with means, illustrated as a turret for carrying gages having different shapes, the turret being constructed and arranged to facilitate 55 the selecting and positioning of the gages relatively to the grooving means and the heel supporting means.

In its method aspect, as herein exemplified, the invention is recognized in forming 60 grooves in the breasts of Cuban heels near one of the breast corners of the heel and following substantially the contours of the breast corners, which consists in positioning a heel relatively to a grooving means by 65 utilizing as positioning elements the breast of the heel and a portion of the side of the heel adjacent to that breast corner of the heel near which the groove is to be formed, and moving the heel past the grooving means 70 to form a groove in the heel breast near said corner while utilizing the heel breast and said portion of the side of the heel as guiding elements to determine the path of the heel.

The machine illustrated as embodying the 75 invention, and with the aid of which the invention may be advantageously practiced, will now be described with reference to the drawings.

Fig. 1 is a front elevational view of the illustrated machine, parts being broken away to show the interior construction thereof;

Fig. 2 is a plan view of the machine;

Fig. 3 is a perspective view of a heel the breast of which has been grooved by the machine illustrated in Figs. 1 and 2;

Fig. 4 shows a construction for forming grooves in the breasts of heels at different angles of inclination to the breast surfaces of heels; and

Fig. 5 is a detail view of the machine illustrated in Figs. 1 and 2 showing the heel supporting table and the grooving means.

The illustrated machine is constructed and arranged to form heel cover receiving grooves 100

or slats A (Fig. 3) in the breast B of a Cuban heel C substantially parallel and adjacent to their respective breast corners D formed by the junction of the breast B and the sides of the heel, one of which is indicated by the reference character E.

The machine includes a standard 12 (Fig. 1) having a central upwardly extending portion 14 upon which is mounted a table 16 for supporting a heel C placed breast down thereon, and two laterally extending portions 18 for supporting relatively to the table 16 circular saws 20 extending above or beyond the table (Fig. 1) and gages 22 which are arranged to engage the sides of the heels and to serve as guides when a heel is moved over the table 16 past the saws 20.

In order that the grooves A may be successively formed adjacent to each of the breast corners or edges D while the heel is moved in one general direction along the table 16, the illustrated machine includes a pair of groove forming units (Fig. 2) cooperatively positioned out of alignment with one another on opposite sides of the table 16. Since the units are substantial duplicates of one another except insofar as certain of their parts are reversed, it will be necessary to describe but one of the units.

The table 16 has a flat upper surface 24 constructed and arranged to be engaged by opposite breast corners D of heels in order that each of the heels may be fixed against rotation about its vertical axis when placed breast downwardly on the table, thus insuring that the saw will enter the heel breast at a predetermined angle. The table is provided with recesses 26 (Fig. 5) having dovetailed portions 28 along their sides, which recesses extend partly across the width of the table and are constructed to receive slides 30 (Figs. 1 and 5) each slide having its inner end portion cut away to form an opening 34 (Fig. 1) for the reception of one of the saws 20.

Mounted upon each of the laterally extending portions 18 of the standard 12 is a block 36 (Fig. 1) having an opening 38 extending therethrough. Passing through and secured within the opening 38 is a bronze bearing 40 which serves rotatably to support a shaft 42 carrying at its outer end a pulley 44 adapted to be connected with a source of power. The opening 38 in the block 36 includes an oil well 46 for purposes of lubrication.

The shaft 42 is provided with an end section 48 of reduced diameter which has a threaded recess 50 in its end for the reception of a screw 52 (Fig. 1) to force the saw 20 tightly against the end of the shaft 42 so that the saw will rotate therewith.

In order to support the gages 22 the block 36 is provided with upwardly extending portions 54 and 56 (Fig. 1) which serve to support a turret 57 having a downwardly extending portion 58 the lower face of which

is arranged to seat upon the top face of the upwardly extending portion 54 of the block 36. The upwardly extending portion 56 of the block 36 has a dowel retaining sleeve 59 threaded thereon to limit upward movement of a dowel pin 60 which is slidable in a recess 62 in the upwardly extending portion 56 and is urged upwardly against the sleeve 59 by a spring 64.

The turret 57 includes a plurality of arms 68 (Figs. 1 and 2) and gage attaching portions 70 (Fig. 2) upon which portions gages 22 are mounted. Each arm 68 is provided with a tapered dowel pin receiving recess 72 (Fig. 1) arranged to receive the dowel pin 60 for circumferentially locating the turret selectively to position any one of the gages 22 in heel guiding relation to the table 16 and saw 20.

The turret 57 may be rotated about a stub shaft 74, fixed to the upwardly extending portion 54 of the block 36 by a pin 76 and passing vertically through the turret 57 which is provided with an opening 78 for receiving the stub shaft 74.

In order to clamp the turret 57 in operative position (Fig. 1), the stub shaft 74 is provided with a cam 90 which is pivotally mounted upon a bifurcated portion 86 (Fig. 2) of the stub shaft 74 through a pin 88. For conveniently operating the cam 90 a handle 92 is formed integral with the cam, which handle when rotated in a counterclockwise direction, as shown by dotted lines in Fig. 2, will release the cam 90 so as to allow the turret to be raised to the position indicated in dotted lines in Fig. 1. The cam 90 may be constructed and arranged for direct engagement with the top surface of the turret itself, but it has been found convenient to attach a washer 89 of relatively soft material upon the upper surface of the turret to afford better clamping action between the turret 57 and the cam 90.

In order to assist in selectively positioning the gages 22 adjacent to the supporting table 16, the machine is provided with a spring 80 which encircles the upwardly extending portion 54 of the block 36 and the downwardly extending portion 58 of the turret 57, the ends of the spring 80 being in contact with faces 82 and 84 of the turret and the block, respectively, thereby tending normally to urge the turret 57 away from the block 36 to raise the turret so that the dowel pin receiving recess 72 is raised from the dowel pin 60 upon release of the cam 90, thus leaving the turret 57 in a position for conveniently rotating it upon the stub shaft 74.

Each of the gages 22 is of substantial height and has an arcuate heel engaging face 100 (Fig. 2) which is spaced from the saw 20 and retreats upwardly from said saw when in operative position (Fig. 1) adjacent to the surface of the table.

In the manufacture of wooden heels it is necessary to abrade or "spool" the lower side portions of heels near the breast corners to reduce the width of the lower portions of the heel breasts. Since the "spooling" is usually carried out by hand, the curvatures of the sides of heels are not always uniform. It is desirable that the groove A should follow its respective breast corner throughout the length of the groove and for this reason it is necessary that the face 100 of the gage 22 should engage the heel as close to the breast corner of the heel as practicable. Since the arcuate faces 100, above described, retreat upwardly away from the heel, as shown in Fig. 1, each gage 22 contacts with the side of the heel only along a line close to a breast corner thereof, thus insuring the forming of a groove A which is of equal distance from the breast corners throughout its length. Contact with portions of the side of the heel which are remote from the breast corner and the curvature of which may be different from the curvature of the breast corner itself is thus avoided.

The arcuate outside faces 100 of the various gages 22 on the turret 57 are of different contours or curvatures to accommodate different types and sizes of heels and the operator may conveniently select the gage having a curvature corresponding to the curvature of the heel which is to be grooved.

When it is desired to change gages, the handle 92 is swung to the left (Fig. 1), thereby allowing the spring 80 to raise the turret 57. The turret 57 is then rotated upon the stub shaft 74 until the selected gage is in its proper position over the table 16. The gage is next lowered in its proper circumferential position adjacent to the surface 24 of the table by swinging the handle 92 to the right, the dowel pin 60 thus engaging the dowel pin receiving slot 72 in the arm 68 corresponding to the selected gage.

In order to vary the distances between the breast corners D of different heels and the grooves A, each saw 20 may be moved within its corresponding opening 34 in the direction of the width of the table 16 thereby changing the distance between the arcuate face 100 of the gage member 22 in position upon the table and the saw 20. A split collar 102 is mounted upon the shaft 42 and the shaft is provided with an axially extending recess 104 arranged to receive a set screw 106 carried by the pulley 44, the recess 104 being wide enough to provide for positioning the pulley in different positions along the shaft. When the saw has been positioned at the desired distance from the gage 22, it is fixed in the adjusted position by sliding the split collar 102 and the pulley 44 along the shaft and against the ends of the bronze bearing 40 and securing them to the shaft for rotation therewith

to provide against movement of the shaft lengthwise thereof.

As previously stated, in order to avoid any tendency toward splitting the heel, such as might otherwise result from locating the marginal grooves A throughout their depth near the breast corners of the heel, it is often desirable to form the grooves in the breasts of the heels at varying angles transversely of the heel relatively to the breast surfaces of the heels and substantially following the contours of the heel breast edges. To this end, as illustrated in Fig. 4, the machine may be provided with a table 106, which table 106 is split along its center line into two sections 108 each of which, together with a gage 110 which rests upon it, may be tilted at various angles to the saw 20 so that during various grooving operations the saw may enter the heel at varying angles.

In order to allow the table 106 and the gage 110 to be conveniently tilted relatively to the saw 20, each gage 110 is provided with a recessed portion 112 and each section of the table 106 is provided with a slot 114 for the reception of the reduced portion 48 of the shaft 42 as relative tilting takes place between the shaft and the table and gage. The degree of tilting of each section of the table 106 may be changed by any convenient means such as a segment of a gear 116 which engages a worm 118 rotated through a worm shaft 120 to tilt each of the table sections 106 and the gages 22 at any desired angle relatively to its corresponding saw 20.

In carrying out the grooving operation, a heel C (Fig. 2) is moved along the surface 24 of the table 16 with its breast face down upon the table 16 or 106 and the portion of one side E of the heel adjacent to one breast edge D of the heel engages the lower edge of the arcuate face of one of the gages 22 or 110 and is moved past the corresponding saw 20 to form a groove A. The illustrated heel breast B is concaved so that the heel engages the table only along its breast corners D. The heel breast, however, may be only slightly concaved or flat, in which case the heel will engage the table over a substantial portion of the breast of the heel.

By providing a pair of heel grooving units having gages disposed at opposite sides of a common table (Figs. 1 and 2), a groove may be formed in the breast of a heel close to one breast corner thereof and following the contour of that breast corner, as above indicated, and by continuing the movement of the heel in the same general direction along the surface of the table in engagement with the other gage and past the other grooving means, a groove may be formed in the breast of the heel adjacent to the other breast corner and following the contour of that breast corner.

Having described the invention, what I

claim as new and desire to secure by Letters Patent of the United States is

5. The method of forming heel cover receiving slots in the breast of a heel which consists in positioning a heel relatively to slot forming means and effecting movement of the heel continuously in the same general direction while utilizing a portion of the breast of the heel and a side of the heel as 10 guiding elements to form successively in the breast of the heel a pair of heel cover receiving slots, one of which is substantially parallel to one of the breast edges of the heel and the other of which is substantially parallel 15 to the other breast edge of the heel.

2. The method of forming heel cover receiving slots in the breast of a heel which consists in positioning a heel relatively to slot forming means and effecting movement 20 of the heel continuously in the same general direction while utilizing both breast edges of the heel and a side of the heel as guiding elements to form successively in the breast of the heel a pair of heel cover receiving slots, 25 one of which is substantially parallel to one of the breast edges of the heel and the other of which is substantially parallel to the other breast edge of the heel.

3. The method of forming a heel cover receiving slot in the breast of a heel near one 30 of the breast corners of the heel and following substantially the contour of said breast corner which consists in positioning a heel relatively to a slotting means by utilizing simultaneously as positioning elements both 35 breast corners of the heel and a portion of the side of the heel adjacent to the breast corner near which the slot is to be formed and then progressively moving the heel past the slotting means to form a heel cover receiving slot in the heel breast near said corner while utilizing simultaneously both breast corners and said portion of the side of the heel as 40 guiding elements to determine the path of movement of the heel past said means.

4. A machine for forming heel cover receiving grooves in the breasts of heels having, in combination, means for supporting a heel, grooving means extending beyond the 50 supporting means, and a gage having an elongated curved portion shaped and arranged to engage the side of a heel supported by said first-named means and to control the path of movement of the heel relatively to said first-named means and past the grooving means to 55 form in the breast of the heel a heel cover receiving groove.

5. A machine for forming heel cover receiving grooves in the breasts of heels having, 60 in combination, means for supporting a heel, a circular saw extending beyond the supporting means, and a gage having an elongated curved portion shaped and arranged to engage the side of a heel supported by said first-named means and to control the path of move-

ment of the heel relatively to said first-named means and past the circular saw to form in the breast of the heel a heel cover receiving groove.

6. A machine for forming heel cover receiving grooves in the breasts of Cuban heels having, in combination, means for engaging the opposite breast corners of a heel positively to support the heel against axial rotation, grooving means extending beyond said means, and 75 a gage constructed and arranged to engage a side of the heel adjacent to a breast corner thereof to facilitate the guiding of the heel over the first-named means as the heel is moved past the grooving means to form a 80 groove in the breast of the heel.

7. A machine for forming heel cover receiving grooves in the breasts of Cuban heels having, in combination, a table for supporting the opposite breast corners of a heel 85 placed downwardly upon the table positively to support the heel against axial rotation, grooving means extending above the table, and a gage constructed and arranged to engage a side of the heel adjacent to a breast corner thereof to facilitate the guiding of the heel upon the table as the heel is moved past the grooving means to form in the breast of the heel a groove extending parallel to said breast corner.

8. A machine for forming heel cover receiving grooves in the breasts of Cuban heels having, in combination, a table having a substantially flat surface for supporting a heel placed breast downwardly upon said surface, 100 grooving means extending above the supporting surface, a gage spaced from the grooving means and having an elongated curved portion shaper and arranged to engage a side of a heel supported by said table and to control the path of movement of the heel relatively to said table and past the grooving means to form in the breast of the heel a heel cover receiving groove.

9. A machine for forming heel cover receiving grooves in the breasts of Cuban heels having, in combination, a table having a surface for supporting a heel placed breast downwardly upon said surface, heel grooving means extending above the supporting surface, and a gage positioned adjacent to the supporting surface and spaced from the grooving means, said gage having an elongated curved portion shaped and arranged to engage a side of a heel supported by said table and to control the path of movement of the heel relatively to said table and past the grooving means to form in the breast of the heel a heel cover receiving groove, said surface being shaped to retreat from the grooving means for contacting with the side of the heel along substantially a line adjacent to the breast corner of the heel as the grooving operation progresses.

10. A machine for forming heel cover re-

- ceiving grooves in the breasts of Cuban heels near the breast corners of the heels and following substantially the contours of the breast corners having, in combination, a table 5 for supporting a heel placed breast down upon the table, grooving means extending above the table, a turret mounted for rotation, gages carried by said turret, said gages being constructed and arranged for positioning 10 adjacent to the table and spaced from the grooving means to facilitate the guiding of the heel upon the table past the grooving means to form said grooves, and means for clamping the turret against rotation in the 15 aforesaid position.
11. A machine for forming heel cover receiving grooves in the breasts of Cuban heels near the breast corners of the heels and following substantially the contours of the breast corners having, in combination, a table 20 for supporting a heel placed breast down upon the table, a circular saw extending above the table, a turret mounted for rotation, gages carried by said turret, said gages being 25 constructed and arranged for positioning adjacent to the table and spaced from the circular saw to facilitate the guiding of the heel upon the table past the circular saw to form said grooves, and means for clamping the 30 turret against rotation in the aforesaid position.
12. A machine for forming heel cover receiving grooves in the breasts of Cuban heels, near the breast corners of the heels and following substantially the contours of the breast corners, having, in combination, a table 35 having a substantially flat surface for supporting a heel placed breast down upon said surface, grooving means extending above the table, a gage positioned adjacent to the table and spaced from the grooving means to facilitate the guiding of a heel over the table and past the grooving means, said gage having an arcuate engaging face upwardly retreating from the grooving means 40 to insure contact with the side of the heel adjacent to a breast corner thereof, and means for tilting the table and the gage relatively to the grooving means to vary the angle at which the grooving means enters the heel.
13. A machine for forming heel cover receiving grooves in the breasts of Cuban heels near the breast corners of the heels and following substantially the contours of the heel breast corners having, in combination, a table 45 for supporting a heel placed breast down upon the table, a circular saw extending above said table, a turret mounted for rotation, gages carried by said turret for facilitating the guiding of the heel over the table and past the circular saw, each of the gages having an arcuate heel engaging face which is 50 upwardly retreating from the grooving means when in operative position and being constructed and arranged for contact with a side of the heel adjacent to a heel breast corner of the heel, said turret being arranged to
- position any one of the gages adjacent to the table and spaced from the saw, means for adjusting the machine to vary the distance of the groove in the breast of the heel relatively to a breast corner, and means for clamping the turret to position any one of the gages adjacent to the supporting table at a predetermined distance from the grooving means. 55
14. A machine for forming heel cover receiving grooves in the breasts of Cuban heels near the breast corners of the heels and following substantially the contours of the heel breast corners having, in combination, a table 60 for supporting a heel placed breast down upon the table, a circular saw extending above said table, a turret mounted for rotation, gages carried by the turret for facilitating the guiding of the heel over the table and past the saw, each of said gages being arranged for positioning adjacent to the table and spaced from the saw, means for adjusting the machine to vary the distance between the saw and the gages, and means for clamping the turret to position any one of the gages adjacent to the table at a predetermined distance from the saw. 65
15. A machine for forming heel cover receiving grooves in the breasts of Cuban heels, near the breast corners of the heels and following substantially the contours of the heel breast corners having, in combination, a table 70 for supporting a heel placed breast down upon the table, grooving means extending above the table, a gage positioned adjacent to the table and spaced from the grooving means to facilitate the guiding of a heel over the table and past the grooving means, said gage having an arcuate engaging face upwardly retreating from the grooving means to insure contact with the side of the heel adjacent to a breast corner thereof, and means for tilting the table and the gage relatively to the grooving means to vary the angle at which the grooving means enters the heel. 75
16. A machine for forming heel cover receiving grooves in the breasts of Cuban heels near the breast corners of the heels and following substantially the contours of the breast corners having, in combination, a table 80 for supporting a heel placed breast down upon the table, grooving means extending above the table, a gage spaced from the grooving means and constructed and arranged for engaging the side of the heel to facilitate the guiding of the heel over the table and past the grooving means, means for adjusting the machine to vary the distance between the gage and the grooving means to change the position of the groove relatively to a breast corner of the heel, and means for tilting the table and the gage relatively to the grooving means to vary the angle at which the grooving means enters the heel. 85
17. A machine for forming heel cover receiving grooves in the breasts of Cuban heels 85

near the breast corners of the heels and following substantially the contours of the breast corners having, in combination, a table for supporting a heel placed breast down upon the table, a circular saw extending above the table, a gage spaced from the circular saw and constructed and arranged for engaging the side of the heel to facilitate the guiding of the heel over the table and past the circular saw, means for adjusting the machine to vary the distance between the gage and the circular saw to change the position of the groove relatively to a breast corner of the heel, and means for tilting the table and the gage relatively to the circular saw to vary the angle at which the circular saw enters the heel.

18. A machine for forming heel cover receiving grooves in the breasts of Cuban heels near the breast corners of the heels and following substantially the contours of the breast corners having, in combination, a table for supporting a heel placed breast down upon the table, grooving means extending above the table, a gage spaced from the grooving means and constructed and arranged for engaging the side of the heel to facilitate the guiding of the heel over the table and past the grooving means, and means for tilting the table and the gage relatively to the grooving means for varying the angle at which the grooving means enters the heel.

19. A machine for forming heel cover receiving grooves in the breasts of Cuban heels near the breast corners of the heels and following substantially the contours of the breast corners having, in combination, a table for supporting a heel placed breast down upon the table, grooving means extending above the table, and a gage spaced from the grooving means and constructed and arranged for engaging the side of the heel to facilitate the guiding of the heel over the table and past the grooving means, said table together with the gage and the grooving means being mounted for tilting movement relatively to each other for varying the angle at which the grooving means enters the heel.

20. A machine for forming heel cover receiving grooves in the breasts of Cuban heels near the breast corners of the heels and following substantially the contours of the heel breast corners having, in combination, a table for supporting a heel placed breast down upon the table, grooving means extending above the table, a gage spaced from the grooving means and constructed and arranged to engage the side of the heel to facilitate the guiding of the heel over the table and past the grooving means, means for adjusting the machine to vary the distance between the gage and the grooving means for changing the position of the groove relatively to a breast corner, and means for tilting the table and the gage relatively to the grooving means

for varying the angle at which the grooving means enters the heel.

21. A machine for forming heel cover receiving grooves in the breasts of Cuban heels near the breast corners of the heels and following substantially the contours of the breast corners of the heels having, in combination, a table having a substantially flat surface upon which a heel is placed breast down upon the surface, grooving means extending above said surface, a gage positioned adjacent to said surface and spaced from the grooving means to facilitate the guiding of the heel over the surface and past the grooving means, said gage being constructed and arranged for engagement with the sides of the heel near a breast corner thereof, and means for tilting the table and the gage relatively to the grooving means for varying the angle at which the grooving means enters the heel.

22. A machine for forming heel cover receiving grooves in the breasts of Cuban heels near the breast corners of the heels and following substantially the contours of the breast corners of the heels having, in combination, a table for supporting a heel placed breast down upon the table, grooving means extending above the table, a gage mounted upon the table and spaced from the gage to facilitate the guiding of the heel over the table and past the grooving means, and means for tilting the table and the gage relatively to the grooving means for varying the angle at which the grooving means enters the heel.

23. A machine for forming heel cover receiving grooves in the breasts of Cuban heels near the breast corners of the heels and following substantially the contours of the heel breast corners having, in combination, a heel support, grooving means extending above the support, means for engaging the heel to facilitate the guiding of the heel over the support and past the grooving means, and a turret constructed and arranged for carrying the heel engaging means and positioning the same relatively to the support and the grooving means.

24. A machine for forming heel cover receiving grooves in the breasts of Cuban heels near the breast corners of the heels and following substantially the contours of the heel breast corners having, in combination, a heel support, grooving means extending above the support, gages constructed and arranged to facilitate the guiding of the heel over the support and past the grooving means, and a turret constructed and arranged for carrying the gages and assisting the operator selectively to position any of the gages relatively to the support and the grooving means to fit the machine for the grooving operation.

25. A machine for forming heel cover receiving grooves in the breasts of Cuban heels near the breast corners of the heels and fol-

lowing substantially the contours of the heel
breast corners having, in combination, a heel
support, grooving means extending above the
support, a plurality of gages constructed and
5 arranged to facilitate the guiding of the heel
over the support and past the grooving
means, and a turret constructed and ar-
ranged for carrying the gages and assisting
the operator selectively to position and clamp
10 any of the gages relatively to the support and
the grooving means to fit the machine for the
grooving operation.

26. A heel grooving machine having, in
combination, a table for supporting a heel
15 breast downwardly upon the table, a circular
saw projecting above the table, an elongated
gage extending along the table for a substan-
tial distance beyond the saw and constructed
and arranged to engage a side of the heel
20 placed upon the table along a substantial
portion of a breast corner of the heel, said
gage being constructed and arranged to posi-
tion the heel upon the table relatively to the
saw and to control the path of movement of
25 the heel over the table and past the saw to
form in the breast of the heel a heel cover
receiving groove.

27. A heel grooving machine having, in
combination, grooving means, a table above
30 which the grooving means extends, a gage
having an elongated portion constructed and
arranged to engage a side of a heel placed
upon the table along substantially the entire
breast corner of the heel, said portion of the
35 gage having a curvature corresponding to
the portion of the heel with which it is to en-
gage for controlling the path of movement
of the heel over the table and past said
grooving means to form in the breast of the
40 heel a groove having substantially the same
curvature as said portion of the gage.

28. A grooving machine having, in com-
bination, grooving means, and members each
of which has a surface angularly disposed
45 relatively to a surface of another member,
one of the surfaces being curved lengthwise
thereof, and extending a substantial distance
at opposite sides of the grooving means for
positioning a heel relatively to the grooving
50 means and for guiding the heel past the same
to form in the heel, as the heel in contact with
said surfaces is moved past the grooving
means, a heel cover receiving groove having
a curvature corresponding to the lengthwise
55 curvature of said curved surface.

In testimony whereof I have signed my
name to this specification.

LEWIS J. BAZZONI.
